UNITED STATES PATENT OFFICE

2,516,417

FLEXIBLE STOCK FOR PICTURE FRAMES

Leopold Rado, London, England

Application February 19, 1948, Serial No. 9,593
In Great Britain May 5, 1947

1 Claim. (Cl. 40—152)

1

This invention relates to material for use in forming a frame or surround for pictures, display cards, mirrors or the like.

It is well known to frame pictures or the like by means of passe-partout, which comprises a strip of paper or fabric coated with adhesive on one side, which is folded over the edge of the glass and backing panel of the picture and stuck to these parts.

The passe-partout method has the advantage of being an economical method of framing, which is easily applied as the passe-partout strip is available in reel form. It has, however, the disadvantage that it provides a flat surround or frame and has none of the pleasing characteristics of the conventional wooden, metallic, or like rigid frames.

It is an object of the present invention to provide an improved form of strip framing material, which may be used to simulate the raised effect of the wooden or metal frames but which is sufficiently flexible to be wound into reels.

According to the present invention framing material for use in forming a frame or surround of a picture or the like comprises a strip of flexible material one face of which is coated with an adhesive compound and the other face of which is provided with a raised flexible beading or the like extending longitudinally of the strip.

To enable the invention to be fully understood it will now be described with reference to the accompanying drawings, in which:

Fig. 1 is a perspective view of a section of a strip according to one embodiment of the invention,

Fig. 2 is a similar view of a modified form of strip,

Fig. 3 is a perspective view of a reel of a strip according to a further modification of the invention,

Fig. 4 is a perspective view of the under or adhesively-coated side of the strip according to Fig. 1,

Fig. 5 is a fragmentary plan view of a picture framed by means of the strip shown in Fig. 1, and Fig. 6 is a section on the line 6—6 of Fig. 5.

As shown in the accompanying drawing, the framing material comprises a strip 1 of flexible material in the form of a raised beading or the like which is bonded by suitable means to the upper face of a flexible strip 2 of paper, fabric, or other suitable material, which is wider than the strip 1 and is provided with a coating of an adhesive compound on its under face 3.

As shown in Fig. 1 the strip 1 is of stepped form

in cross section. The strip 1, shown in Fig. 2 is similar in outward appearance to that of Fig. 1 but is hollow and formed with a longitudinal channel 4. A further modified form of strip is shown in Fig. 3 and comprises a series of raised parallel ribs or corrugations 1a.

In all cases the strip 1, which is adapted to form the actual frame or surrounds of the pictures or the like, is narrower than the strip 2 and extends continuously along one longitudinal edge thereof.

Figs. 5 and 6 show the strip applied to form a frame of a picture. To form the frame, portions of the material are cut from a continuous length 15 of the material such as the reel shown in Fig. 3, and the ends of the portions cut to form corner joint edges 9 extending at an angle of 45° to the edge of the strip. In forming the frame, one of the portions of the strip of material a is positioned on the glass 6 which covers the picture 7, the edge 1b of the strip extending along the edge of the glass and the strip being stuck to the glass by the adhesive coating on the underface 3. The outwardly extending portion of the strip 2 is then folded over the panel 8 at the back of the picture and pressed flat to make the adhesive coating adhere to the panel 8. Another portion b of the framing material is positioned and stuck to the adjacent edge of the glass 6 and panel 8, the edges 9 being positioned in abutment at the corner, as shown in Fig. 5. Further portions of the material are secured along other edges of the picture (not shown), to provide a complete frame or surround, which is of raised form, simulating a rigid wooden or metal frame.

To facilitate the cutting of the framing material to form the 45° corner joints, the under face 3 of the strip 2 is formed with a series of lines 5, which intersect to form a lattice-like pattern. The lines intersect one another at right angles and form an angle of 45° with the longitudinal edges of the strip 2.

The strip 1 may be formed of any suitable material which is sufficiently flexible to permit the strip to be wound into a reel as shown in Fig. 3. If desired, it may be formed of resinous material, for example a vinyl resin such as polyvinyl chloride and the strip may be produced by extrusion, moulding or other operations.

What I desire to claim by Letters Patent of the United States is:

Strip framing material for pictures comprising a strip of flexible material one face of which is coated with an adhesive compound and on the opposite face thereof a raised flexible beading

with parallel ribs extending along one longitudinal edge of the strip and across only part of the width of the strip.
